UNITED STATES PATENT OFFICE

132,769

DESIGN FOR A WELDING MACHINE

Joseph A. Fotie, Kansas City, Mo.

Application August 26, 1941, Serial No. 102,967

Term of patent 7 years

To all whom it may concern:

Be it known that I, Joseph A. Fotie, a citizen of the United States, residing at Kansas City, in the county of Jackson and State of Missouri, have invented a new, original, and ornamental Design for a Welding Machine, of which the following is a specification, reference being had to the accompanying drawings, forming part thereof, in which

Fig. 1 is a perspective view of the welding machine, showing the new design.

Fig. 2 is a side elevational view of the welding machine illustrating the side thereof not shown in Fig. 1, and

Fig. 3 is a rear elevational view of the machine.

I claim:

The ornamental design for a welding machine, substantially as shown.

JOSEPH A. FOTIE.
